UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

PEDESTAL GUN-MOUNTING.

1,071,607.

Specification of Letters Patent. Patented Aug. 26, 1913.

Application filed June 10, 1911. Serial No. 632,338.

To all whom it may concern:

Be it known that we, ARTHUR TREVOR DAWSON, knight, and GEORGE THOMAS BUCKHAM, both subjects of the King of Great Britain, residing at 32 Victoria street, Westminster, in the county of London, England, have invented certain new and useful Improvements in or Relating to Pedestal Gun-Mountings, of which the following is a specification.

This invention relates to pedestal gun mountings of the kind in which there is provided a clamping device comprising a band that is attached to the pedestal and is furnished with suitable means whereby it can readily either be tightened against the training worm wheel to hold it rigid with the pedestal, or can be slackened so that relative movement can take place between the said worm wheel and the pedestal and the gun be thus rendered capable of being moved rapidly through large training angles.

According to the present invention we so construct a pedestal mounting of the above stated kind that the clamping band is arranged inside the pedestal instead of outside as heretofore. The said band is adapted to be operated by a handle or the like arranged externally with regard to the pedestal. The training worm wheel with which the clamping band co-operates may be provided with a boss which is disposed between the pedestal and the center pivot of the gun. By reason of this arrangement the clamping band is effectively protected by the pedestal from injury resulting from blows and the influence of the weather.

In order that the said invention may be clearly understood and readily carried into effect we will describe the same more fully with reference to the accompanying drawings, in which:—

Figure 1 is a sectional elevation and Fig. 2 a horizontal section taken approximately on the line 1—1 of Fig. 1, showing a constructional form of the invention.

A is the pedestal mounting, B is the training worm wheel and B' its boss, C is the clamping band adapted to engage with said boss. The boss B' of the worm wheel is disposed between the pedestal A and the bush a for the center pivot of the gun, and the clamping band C which surrounds the said boss is provided with a strip c, the lug c' of

which is disposed in a recess a' in the pedestal. A screw threaded pin C' passes through the pedestal, and the lug c' and retains the clamping band C in position. The free ends of the said band are provided with strips C², C^{2x} having lugs c², c^{2x} through which and through the pedestal, passes a horizontally arranged bolt D. The said bolt may be reduced in diameter as shown in Fig. 2 to form a shoulder d which bears against the lug c². The said bolt may be provided with a key d' which engages in a corresponding key-way in the lug c². One end of the said bolt is formed with a knurled head d² which projects beyond the face of the pedestal and provides for the ready withdrawal of the bolt D when required. The other end is screw threaded to receive an internally screw threaded sleeve d^x, to the outer end of which an actuating handle or lever D^x is attached, the said handle or lever being situated outside the pedestal as shown. The bolt D and the screw threaded sleeve d^x are supported in bearings E, the latter being secured to the pedestal. The angular movement of the said handle or lever D^x in one direction causes the lugs c², c^{2x} to move toward each other to tighten the clamping band C on the boss B', and in the other direction allows them to separate so as to slacken the said band from the boss.

What we claim and desire to secure by Letters Patent of the United States is:—

1. In a gun mounting, the combination with the pedestal and the training worm wheel, of a clamping band engaging with the said worm wheel and arranged inside the pedestal, and means arranged tangentially to said band and carried by the pedestal for tightening and slackening the said clamping band with respect to the worm wheel.

2. In a gun mounting, the combination with the pedestal and the training worm wheel, of a boss on the said worm wheel, a clamping band engaging with the said boss and arranged inside the pedestal, and means arranged tangentially to said band and carried by the pedestal for tightening and slackening the said clamping band with respect to the boss.

3. In a gun mounting, the combination with the pedestal and the training worm wheel, of a clamping band engaging with the said worm wheel and arranged inside

the pedestal, means arranged tangentially to said band and carried by the pedestal for tightening and slackening the said clamping band with respect to the worm wheel, and a handle on the exterior of the pedestal for operating the said means.

4. In a gun mounting, the combination with the pedestal, the center pivot of the gun and the training worm wheel, of a boss 10 on the said worm wheel arranged between the pedestal and the center pivot, a clamping band engaging with the said boss and arranged inside the pedestal, and means arranged tangentially to said band and carried by the pedestal for tightening and slackening the said clamping band with respect to the boss of the training worm wheel.

5. In a gun mounting, the combination with the pedestal, the center pivot of the 20 gun and the training worm wheel, of a boss on the said worm wheel arranged between the pedestal and the center pivot, a clamping band engaging with the said boss and arranged inside the pedestal, means arranged tangentially to said band and carried by the pedestal for tightening and slackening the said clamping band with respect to the said boss of the training worm wheel, and a handle on the exterior of the 30 pedestal for operating the said means.

6. In a gun mounting, the combination with the pedestal and the training worm wheel, of a clamping band engaging with the said worm wheel and arranged inside the pedestal, means for attaching the said clamping band to the pedestal, two free ends of the said band, and means arranged tangentially to said band and carried by the pedestal for causing the said free ends to approach and recede to tighten and slacken the band with respect to the training worm 40 wheel.

7. In a gun mounting, the combination with the pedestal and the training worm 45 wheel, of a clamping band engaging with

the said worm wheel and arranged inside the pedestal, means for attaching the said clamping band to the pedestal, two free ends of said band, a bolt passing through the said free ends, said bolt being arranged tangentially to said band and being carried by the pedestal for tightening and slackening the said clamping band with respect to the worm wheel, and a handle on the exterior of the pedestal for actuating the said bolt. 50

8. In a gun mounting, the combination with the pedestal and the training worm wheel, of a clamping band engaging with said worm wheel and arranged inside the pedestal, means for attaching said clamping band to the pedestal, two free ends of said band, a bolt passing through said free ends tangentially to said band, an internally screw-threaded sleeve engaging with said bolt and projecting at one end beyond the 60 pedestal, bearings supported by the pedestal for said bolt and sleeve, and a handle on the projecting end of the screw-threaded sleeve for tightening and slackening the said clamping band with respect to the worm 70 wheel.

9. In a gun mounting, the combination with the pedestal and the training worm wheel, of a ring of armor at the upper end of said pedestal, a boss on said worm wheel 75 disposed inside said ring, a clamping band engaging with said boss, a lug on the clamping band disposed in a recess in the ring, a pin passing vertically through the ring and through the lug, two free ends of said band, 80 a bolt passing through said free ends, and a handle on the exterior of the pedestal for actuating said bolt.

In testimony whereof we affix our signatures in presence of two witnesses.

ARTHUR TREVOR DAWSON.
GEORGE THOMAS BUCKHAM.
